(57) **CLAIM**

The ornamental design for an automobile, as shown and described.

DESCRIPTION

FIG. 1 is a right side view of an automobile showing my new design;

FIG. 2 is a left side view thereof;

FIG. 3 is a front view thereof;

FIG. 4 is a rear view thereof;

FIG. 5 is a top plan view thereof;

FIG. 6 is a first perspective view thereof; and,

FIG. 7 is a second perspective view thereof.

A bottom view is omitted as it forms no part of the claimed design. In each drawing, shading is applied on all surfaces for the purpose of specifying a three-dimensional shape.
